UNITED STATES PATENT OFFICE.

GEORGE H. GILMAN, OF BELMONT, MASSACHUSETTS.

DRILLING MACHINE.

Application filed January 6, 1921. Serial No. 435,474.

My invention relates to drilling machines and particularly but not exclusively to a stoping drill for rock.

The invention will be best understood from the accompanying drawings and the following specification of a specific embodiment thereof submitted for illustrative purposes, while its scope will be more particularly pointed out in the appended claims.

10 In the drawings:—

Figure 1 shows in elevation the submitted embodiment of the invention, with parts broken away;

Fig. 2 is a vertical, longitudinal section on an enlarged scale of part of the machine shown by Fig. 1, corresponding to a section on the line 2—2 of Fig. 4;

Figs. 3, 4, 5, 6 and 7 respectively are sections on the lines 3—3, 4—4, 5—5, 6—6 and 20 7—7 of Fig. 2, Fig. 6 for illustrative purposes showing the position of parts when the shafts driving the yokes have moved ninety degrees from the position illustrated by Fig. 2;

25 Fig. 8 is a section on the line 8—8 of Fig. 2 with parts omitted;

Figs. 9 and 10 are diagrams representing the operation of the valve controlling the water supply for the drill steel and the air for the feed cylinder;

30 Fig. 11 is a section on the line 11—11 of Fig. 4;

Fig. 12 is a section corresponding to Fig. 11 with the valve moved to its neutral position; and

35 Fig. 13 is a section corresponding to Fig. 11 with the valve moved to the position in which the hole is blown.

Referring to the drawings, the submitted 40 embodiment of the invention generally comprises a drill steel and fluid pressure operated hammer for moving it longitudinally, a motor for moving it angularly and a feeding device for moving it up to the work.

45 The drill steel 1 is shown as provided with a shank 2 which is received by the chuck 3, the parts being so formed that when the chuck rotates, the drill steel must rotate with it as is usual in devices of this kind. As 50 illustrated, aligned with the chuck is a hammer having the head 4, the rear extension 5 and the hammer bar 6, the latter projecting into the chuck and adapted to strike the shank of the drill steel at the end of the forward stroke of the hammer.

The details of the mechanism for controlling the operation of the hammer are not claimed in this application and therefore this part of the example of my invention illustrated will only be described sufficiently to 60 explain how they are applied to my present invention.

The hammer is supplied with motive fluid through a passage 8 which communicates with the forward portion of the bore receiving the rearward extension 5 of the hammer and through passages 9 with the space at the rearward end of this bore.

From an intermediate portion of the bore and connecting the same with the forward portion of the bore receiving the head 4 of the hammer are shown passages 10 which, when the hammer in its forward travel uncovers their rearward end, admit pressure fluid to the forward portion of the bore receiving the head 4. Motive fluid is admitted to the rearward portion of the bore receiving the head 4 at the end of the rearward travel of the hammer by reason of the reduced diameter portion 11 of the extension 5, establishing communication between such portion and the conduit 8. The intermediate portion of the bore receiving the head 4 is provided with an exhaust port 12 in communication with a passage 13 for conducting the exhaust to the atmosphere. As will be understood by those skilled in the art, exhaust will take place when the head 4 in its reciprocations opens the port 12 to opposite ends of the bore.

For rotating the chuck by power means, the submitted embodiment of my invention includes a fluid operated rotary engine which as shown comprises the abutments 14 and the rotor 15. The details of this part of the machine are not claimed in the present application and will only be described with sufficient particularity to convey an understanding of their application to the submitted embodiment of the invention. The rotor 95 is journaled on the exterior of the casing forming the rearward bore of the cylinder, while the abutments are supported by shafts 16 carrying at their forward end a pair of oppositely disposed eccentrics 17. On the corresponding eccentrics of each shaft I mount the yokes 18 having internal gear teeth 19 that mesh with the external gear teeth 20 formed on the chuck. When the engine is in operation, the shafts and their 100 105 110

eccentrics gyrate the yokes and rotate the chuck at a lesser speed than the shafts. By this construction is afforded a reduction gear.

Any suitable means may be provided for admitting motive fluid to the rotary engine and exhausting it therefrom. For this purpose as illustrated by Fig. 8 the intake conduits 21 are shown in communication with the constant pressure space at the rear end 10 of the cylinder and the exhaust conduits 22 in communication with the ring-like chamber 23, which by means of a passage 23^a is kept in communication with the atmosphere. Fig. 8 only shows the approximate position of the 15 passages 21 and 22, their true positions being shown in Figs. 4 and 5. It will be noticed that the arrangement just described provides that whenever the hammer is supplied with motive fluid to cause it to reciprocate, motive fluid will be supplied to the rotary engine in order that it may rotate the chuck.

The chuck, the hammer and the rotary engine just described are herein housed by a suitable casing providing a bearing for the 25 chuck and rotor and cylinders for the hammer and rotor. This casing as shown comprises a front head section or chuck casing 24, a main cylinder section 25, a rear cylinder section 26, a motor casing or cylinder 30 section 27 for the rotor and a rear head block or section 28. It will be obvious that the casing may be divided to present sections more or less in number than those indicated.

For holding the sections of the casing in assembled relation I have at the sides thereof 35 four through bolts 29. As will be apparent, if the two lower bolts are removed for the purpose of attaching the machine to its feeding device as hereinafter described, the two upper bolts will hold the sections in assembled relation.

The feeding means illustrated for moving the drill steel and its actuating mechanism 45 up to the work comprises a cylinder 30 and a piston or stoping bar which comprises the piston proper 31 and the piston rod 32. The rearward end of the rod 32 is provided with an offset portion 33 having the point 34 in 50 alignment with the drill steel. The feed cylinder has a front head 95 screwed into the cylinder, and a rear head 96 secured to the cylinder by bolts 97. To prevent relative rotation between the rod 32 and the cylinder, the former is made polygonal in cross-section and fits a similarly shaped opening in the head 96. As will be understood by those skilled in the art, the portion 33 is adapted to be secured to a support, for example a mine column, or in the ordinary working of the machine as a stoper, a point 34 will engage the floor of a drift for enabling the drill steel to operate on the roof.

The casing and feed cylinder are shown 65 laterally offset from each other, being herein

arranged side by side in parallel relation to afford a compact machine enabling its use in drifts of limited head room. I have shown the intermediate portion of the casing in contact with the exterior of the cylinder, 70 and for securing the casing to the feed cylinder have provided the latter with spaced pairs of ears 35, which are perforated to receive the projecting ends of the two lower bolts 29. In order to compensate for wear 75 and inaccuracies of manufacture, on the forward projecting ends of the bolts 29 are shown sleeves 36, which are received by the forwardly disposed ears and about the shoulder portions 37 of the chuck casing. When 80 the bolts are tightened by screwing up the nuts 38, the bolt heads 39 force the sleeves against the shoulders 37 and the rear end of the casing against the rearwardly disposed ears. This rigidly connects the casing 85 to the cylinder at one point, and at a spaced point slidably connects it to the cylinder, and further provides an abutment at the rear end of the casing for taking up the thrust of the feeding force.

For rotating the machine manually I have shown the handle 40 provided with a tapered portion 41 engaging a corresponding socket formed in the casing. The handle is held in position by means of the lower bolts 29 which engage suitable recesses 42 formed in the tapered portion of the handle, which recesses provide surfaces extending the width of the handle in contact with the bolts. It will be observed by this construction the handle is immovably keyed by the bolts to the casing. The nut 43 is provided to prevent movement of the handle when the bolts are removed and for binding the handle to the walls of the socket.

In order to permit manual rotation of the drill steel by the handle just described, it is necessary with the present construction to prevent rotation of the chuck, and for this purpose herein is employed a clutch for locking the chuck to its casing. As shown the exterior surface of the chuck has one or more recesses 44 adapted to be engaged by a bolt 45 carried by the chuck casing. When the bolt is in the position of parts shown by Fig. 7, the chuck will be securely locked to the chuck casing. For operating the bolt it has the transversely disposed portion 46 connecting the chuck engaging portion to the parallelly disposed portion 47 sliding in a perforated boss 48 formed on the upper portion of the chuck casing. The end of the portion 47 is provided with a reduced diameter portion 49 and rotatably mounted thereon is a sleeve 50 provided with a handle 51 and held in position by the head 52 of the bolt and the shoulder 53 formed by the reduced diameter portion. Interposed between the sleeve and the end of the counter-bored portion 54 of the boss is a spring 55.

tending to hold the bolt in engagement with the recesses of the chuck. By pressing the handle 51 inwardly, the bolt may be disengaged from the chuck and by releasing the handle the spring will automatically move the bolt into locking position. For holding the bolt in its disengaged position the handle 51 slides through a suitable slot formed in the chuck casing, this slot as illustrated by Fig. 8, comprising the parallel portions 56 and 57 and the connecting portion 58. When the handle is moved into its innermost position, it may be turned transversely relatively to the bolt and moved through the slot 58 into the slot 57 in which position it will be held by means of the spring 55 and the chuck will then be free to rotate.

The drill steel I have shown provided with a bore 59 which extends throughout its length in order to conduct air and water to the hole being drilled for cleansing the same. For conducting water to the drill steel I have shown the tube 60 supported in the back head and extending through the piston 25 into the rearward end of the drill steel. For supporting the tube in the back head I have shown the latter as formed with a rearwardly opening recess 61, said recess being closed by a plug 62 which supports the swivelled 30 water hose connection 63 and at its forward end abuts the flange 64 of the water tube. At the bottom of the recess and surrounding the end portion of the water tube is shown the packing 65.

Herein for controlling the supplies of fluid for operating the feeding mechanism, the hammer, the motor and the supplies of cleansing fluid to the drill steel, are valves 66 and 67, respectively operated by handles 40 88 and 89.

Referring particularly to Figs. 2, 3, 4, 11, 12 and 13, the valve 66 is shown as of the turning plug type having its seat in an extension of the casing section 26. The valve 45 is supplied with motive fluid preferably compressed air through the hose connection 68, in communication with the space 69 at the right hand end of the valve as viewed by Fig. 3. Formed in the valve is a longitudinal passage 70 in constant communication with the space 69 and placing the passage 70 in communication with the exterior surface of the valve are the ports 71 and 72. The valve is further provided with a transverse port 73 which in the position of parts 55 illustrated by Fig. 2 places the exhaust passage 13 in communication with a passage 74 in permanent communication with the atmosphere.

In the position of parts shown by Fig. 2, motive fluid is supplied through the passage 70 and ports 72 to supply the hammer and the chuck rotating motor, while the exhaust from the hammer is permitted to pass from the exhaust passage 13 through the port 73

and passage 74 to the atmosphere. When the valve is moved to the position of parts shown by Fig. 13, the port 72 is moved out of communication with the passage 8 into communication with the passage 13, to 70 which it supplies live motive fluid, which passes into the interior of the chuck through a passage 75 in communication with the passage 13, and finds its way into the drill steel. Fig. 12 shows the neutral position of 75 the valve 67 in which live motive fluid is supplied to neither the passage 8 for operating the hammer nor to the passage 13 for blowing the hole.

For supplying the feed cylinder with air is shown a passage 76 supplied with motive fluid through the port 71 of the valve 66, which port as illustrated by Fig. 11 may be of such size that in all positions of the valve the port will be in communication with said passage. Air is admitted from the passage 76 to the feed by means of the valve 67 which likewise controls the water.

The valve 67 is of the turning plug type provided with a longitudinal passage 77 having the intersecting port 78 adapted to be moved into and out of communication with a passage 79 placed in communication with a passage 80 of the nipple 81 by means of the ring-shaped passage 82, which surrounds the conduits conducting water to the drill bit, as clearly illustrated by Figs. 2 and 4. On the exterior portion of the throttle valve 67 and in the same plane as the transverse passage 78 is an arcuate passage 83 adapted to place the feed in communication with the passage 84 leading to the atmosphere. Placing the water hose connection in communication with the valve seat is a passage indicated in its entirety at 85 100 in Fig. 2 and placing the water tube in communication with the valve seat is a second passage 86. For placing the passages 85 and 86 in communication, the valve 67 is provided with the longitudinally-extending 105 exterior cavity 87. It will be noticed by this construction that the air supplied the passage 76 acts on the end surface of the valve 67 to hold it to its seat and thereby prevents leakage of water and further any leakage which in spite of this may occur will be prevented by the air pressure from leaking into the passages 76 and 79.

Figs. 9 and 10 illustrate diagrammatically 110 the operation of the valve 67. In these figures, the sections *a—a*, *b—b*, correspond to sections on the lines *a—a* and *b—b* of Fig. 2. Fig. 9 illustrates the position of parts when both the steel is supplied with water and the feed is supplied with air. In this position of the parts, the groove 87 establishes communication between the intake and outlet passages 85 and 86 for the water, while the passages 77 and 78 supply 115 the port 79 leading to the feed cylinder 120 125 130

with air. In the position of parts shown by Fig. 10, the groove 87 is moved out of communication with the water passages 85 and 86 and the port 78 is moved out of communication with the passage 79, under which conditions air is no longer supplied the feed cylinder. In this position of parts, the passage 79 is placed in communication with the atmosphere through the passages 83 and 84 and the feed cylinder is exhausted. The valve 67 provides that the feeding pressure may be varied and for this purpose the passages 78 and 83 in the submitted embodiment are so proportioned and relatively disposed that the feed cylinder may be opened more or less to the live air supply or to the atmosphere and each to the exclusion of the other or to both simultaneously. This provides that the supply may be throttled or by simultaneously throttling and exhausting a further reduction in pressure may be secured, also that the air in the feed cylinder may be trapped and if desired its pressure further reduced by exhausting some of it. Depending on the conditions of operation any of these may be effective to regulate the pressure maintained in the feeding cylinder and the force of the feed.

It will be noted that in machines of this character the feeding force holds the tool tightly against the rock and particularly in soft rock acts to prevent turning of the steel. In order that the steel may be readily turned it is of advantage that the air admitted to stop and then advance the hammer piston on its power stroke should move or tend to move back the hammer cylinder to overcome or reduce the feeding pressure. With the present construction the constant pressure on the hammer extension 5 acts gradually to slow up the piston on its rearward stroke, or in effect to reduce its inertia in such manner that the air admitted to the rear of the head 4 to stop and drive the piston forward does not have the same effect in overcoming the feeding force as if the entire rearward surface of the piston were exposed to intermittent pressure. For this reason it is desirable to adjust the feeding pressure to suit the degree of throttling of the air supplied the hammer and the nature of the rock operated upon. It will be appreciated for example that in soft rock the hammer must be throttled to reduce the force of the blow, while the force necessary to turn the steel must be increased and at the same time the action of the hammer which overcomes the feeding effort is reduced by the throttling, thus necessitating a reduction in the feeding effort so as satisfactorily to permit turning of the steel.

Receiving the nipple 81 is a boss 90 providing a socket 91, and for causing a fluid-tight joint between these parts is the U-shaped washer 92 surrounding the nipple

and engaged in a suitable recess in the socket. Establishing communication between the nipple and the forward end of the feed cylinder is a transverse passage 93 and longitudinal passages 94 opening into the feed cylinder at 94^a.

This application discloses improvements upon the inventions disclosed by my pending applications Serial No. 421,748, filed November 4, 1920, Serial No. 442,094, filed February 3, 1921, and Serial No. 407,773, filed September 2, 1920.

Although for purposes of illustration I have described one specific embodiment of my invention, it will be understood that wide deviations may be made therefrom without departing from the spirit of my invention.

I claim—

1. A stoping rock drill of the type which is rotatably supported between oppositely facing portions of the work by a forwardly projecting drill steel and a rearward support engaging part having, in combination, two parallel cylinders, one of said cylinders having therein a reciprocatory hammer piston and having provision for non-rotatably carrying the drill steel, the other of said cylinders having means forming a relatively reciprocable feed piston and feed piston rod, said rod being operatively connected to a part for supporting the machine for rotation about the axial line of the drill steel, said part being non-rotatable relative to the axis of the cylinder carrying said rod.

2. A drilling machine having, in combination, a drilling tool and its operating mechanism, feeding means for said tool comprising extensible, telescopically arranged relatively non-rotatable fluid actuated members, the outer of said telescopically arranged members being secured to said mechanism in lateral offset relation thereto, the other of said members carrying a part in substantial alignment with said tool, said part being formed for rotatably engaging a support.

3. A stoping drill having, in combination, a cylinder, a stoping bar carried by said cylinder in non-rotatable relation thereto, percussive mechanism carried by said cylinder in side by side relation thereto, said mechanism having means for carrying a drill steel, a support engaging member carried by said bar and in operative alignment with said steel, and means for bodily rotating said drill.

4. A stoping drill having, in combination, a relatively non-rotatable feed cylinder member and stoping bar member, tool operating mechanism carried by one of said members in side by side relation, a support engaging part carried by the other of said members in alignment with the tool operated upon, and means for bodily rotating said drill for rotating said tool.

5. A drilling machine having, in combina-

tion, relatively non-rotatable cylinder and piston members, a drilling mechanism carried by one of said members in lateral offset relation thereto, said mechanism having provision for carrying a forwardly extending drilling tool and means for hammering and rotating said tool, and rearwardly arranged means formed for rotatably supporting the other of said members in alignment with said tool.

6. The combination with a sectional percussive drill casing having side bolts for securing the sections of said casing in assembled relation, of feeding means comprising a feed cylinder arranged parallel to said casing, and means for detachably securing said casing and cylinder together, said means preventing substantially relative movement between said casing and cylinder and including attaching means carried by said cylinder for engagement with part only of said bolts, whereby said casing may be detached from said cylinder while holding said sections in assembled relation.

7. In a drilling machine, a percussive apparatus comprising a sectional casing having side bolts for securing the casing sections in assembled relation, cooperating feed cylinder and piston members, said cylinder member being arranged beside said casing and rigidly carrying longitudinally spaced perforated ears, part only of said side bolts passing through said ears for substantially rigidly securing said casing and cylinder member together and for permitting detachment of said casing from said cylinder member while holding said sections in assembled relation.

8. A drilling machine having, in combination, means for carrying a drilling tool, means for imparting percussion to said tool and for rotating it, a casing for said means, an extensible fluid operated feeding device for said tool comprising a feed cylinder arranged in side by side relation to said casing and detachably secured thereto, a feed piston and a feed piston rod non-rotatable relative to said cylinder and adapted to support the machine in alignment with said tool.

9. A drilling machine having, in combination, percussive apparatus including a casing housing a hammer piston and chuck for a drilling tool, a motor for rotating said chuck comprising a motor casing carried by said first mentioned casing, a feeding means for said tool comprising a cylinder and a cooperating piston, said cylinder being arranged in side by side relation to said casing and motor, a plurality of side bolts for securing said motor casing to said first mentioned casing, and means engaging part only of said side bolts for securing both casings to said cylinder, whereby said cylinder may be detached from said casings while holding the latter in assembled relation.

10. A drilling machine having, in combination, parallel feed and percussive casings arranged in side by side relation, a laterally projecting nipple carried by one of said casings and a cooperating socket at the side of the other of said casings, means for holding said casings in relatively fixed assembled relation, and conduits for conducting motive fluid formed in said casings and communicating with each other through said nipple and socket.

11. A drilling machine having, in combination, a feed cylinder and a percussive casing arranged in side by side relation, motive fluid conducting conduits formed in each and opening through registering ports in facing sides, means establishing a fluid tight connection between said ports, means for securing said casing substantially rigidly to said feed cylinder, and a feed piston in said feed cylinder having a rod for engagement with an abutment.

12. A drilling machine having, in combination, a tool actuator comprising sections, through bolts holding said sections together, feeding means for said actuator comprising a feed cylinder, means forming a rigid connection between part only of said bolts and said cylinder, and a sliding connection spaced from said rigid connection between said bolts and feeding means.

13. A drilling machine having, in combination, a tool actuator comprising parts held in assembled relation by a through bolt projecting beyond said casing at opposite ends, feeding means comprising a feed cylinder for said actuator, spaced substantially radially projecting ears carried by said cylinder, one of said ears receiving the projecting end portion of said bolt, a sleeve carried by the oppositely projecting end portion of said bolt, said sleeve received by another of said ears, and means for tightening said bolt to draw the sleeve and first named ear against said casing.

14. A drilling machine having, in combination, means for carrying a drilling tool, an actuator for said tool, fluid pressure actuated feeding means comprising cylinder and piston members, one of said members carrying said actuator in lateral offset relation thereto, the other of said members being operatively connected to means for engaging a support, said means being non-rotatable relative to the member carrying said actuator and providing for rotation of said member about the axial line of said tool.

15. A drilling machine having, in combination, a tool actuator provided with means for carrying a forwardly projecting drilling tool, a rearwardly extending feed piston and rod, the latter arranged in non-rotatable telescopic relation to a forwardly located feed cylinder, said cylinder carrying said actuator in lateral offset relation there-

to, said rod having means for coating with a support for supporting the machine for rotation about the axial line of said tool, and means providing a rotation handle for the machine.

- 5 16. A stoping machine having, in combination, an impact engine having provision for carrying a hollow drill steel projecting from its forward end, an extensible feeding 10 device having a cylinder upon the side of which said impact engine is mounted, said cylinder having mounted therein a reciprocatory piston projecting from the rearward end of said cylinder, means preventing said 15 piston from rotating relative to said cylinder, a tube carried by said impact engine for conducting cleansing fluid for passage through said hollow drill steel, said tube being removable through the rearward end of 20 said impact engine, said piston carrying a supporting portion offset to place it coaxially of said drill steel; said offset portion being so placed as to provide, when the feeding device is extended, sufficient clearance 25 between it and the rearward end of said impact engine to permit said tube to be removed.

17. A stoping machine having, in combination, means for carrying a hollow drill 30 steel, an extensible fluid actuated feeding mechanism having support engaging means in alignment with said steel, an impact engine supported by said hollow drill steel and support engaging mechanism, said impact engine having a tube for conducting 35 cleansing fluid for passage through said hollow drill steel, said tube being removable through the rearward end of said impact engine while said engine is attached to said feeding mechanism.

- 40 18. A rock drilling machine having, in combination, an impact engine having provision for carrying a hollow drill steel, a tube for conducting cleansing fluid for passage through said hollow drill steel, a feeding device for said impact engine, said feeding device having a cylinder and a piston one of which is connected to said impact engine for feeding it and the other of which 45 is arranged to cooperate with a support for the machine located at the rear of said actuator in alignment with said steel, said feeding device being so disposed with relation to said impact engine that said tube may be 50 removed through the rearward end of said impact engine while the latter is connected to said feeding device.

- 55 19. A stoping machine having, in combination, a hammer drill having a chuck formed 60 for carrying a hollow drill steel, a fluid actuated telescopic feeding device having a support engaging portion aligned with said drill steel, said hammer drill being supported by said drill steel and said feeding 65 device, a tube extending axially through

said hammer drill for conducting cleansing fluid from the rearward end to the forward portion thereof for passage through said drill steel, and a connection between said feeding device and hammer drill permitting 70 said tube to be removed through the rearward end of said hammer drill while the latter is attached to said feeding device.

20. A stoping machine having, in combination, an impact engine for actuating a 75 drill steel, a fluid actuated feeding device having a cylinder secured to said engine in lateral offset relation thereto, a piston in said cylinder, a piston rod for said piston movable longitudinally of said cylinder but 80 secured against substantial rotation relative to said cylinder, said rod having a rock engaging point in alignment with the axis of the drill steel, a removable water tube extending through said engine, and means for 85 detachably securing said tube at one end thereof to the rearward end of said engine, said means permitting removal of said tube through the rearward end of said engine.

21. A stoping machine having, in combination, an impact engine for actuating a 90 drill steel, a fluid actuated feeding device having a cylinder secured to said engine in lateral offset relation thereto, a piston in said cylinder, a piston rod for said piston 95 movable longitudinally of said cylinder but secured against substantial rotation relative to said cylinder, said rod having a rock engaging point in alignment with the axis of the drill steel, a removable water tube extending through said engine, and means for 100 detachably securing said tube at one end thereof to the rearward end of said engine, said means permitting removal of said tube through the rearward end of said engine 105 and comprising a removable plug carried by said engine at the rearward end thereof.

22. A stoping machine having, in combination, an impact engine for actuating a 110 drill steel, a fluid actuated feeding device having a cylinder secured to said engine in lateral offset relation thereto, a piston in said cylinder, a piston rod for said piston movable longitudinally of said cylinder but 115 secured against substantial rotation relative to said cylinder, said rod having a rock engaging point in alignment with the axis of the drill steel, a removable water tube extending through said engine, means for detachably securing said tube at one end thereof to the rearward end of said engine, said 120 means permitting removal of said tube through the rearward end of said engine and comprising a removable plug carried by said engine at the rearward end thereof, 125 and a water connection carried by said plug.

23. A stoping machine having, in combination, an impact engine for actuating a 130 drill steel, a fluid actuated feeding device having a cylinder secured to said engine in

lateral offset relation thereto, a piston in said cylinder, a piston rod for said piston movable longitudinally of said cylinder but secured against substantial rotation relative

engaging end for said rod offset into alignment with said drill steel.

- 5 to said cylinder, said rod having a rock engaging point in alignment with the axis of the drill steel, a removable water tube extending through said engine, and means for detachably securing said tube at one end
- 10 thereof to the rearward end of said engine, said means permitting removal of said tube through the rearward end of said engine and comprising a plug removably secured to said engine at the rearward end thereof, one end of said plug adapted to secure said tube and the other end adapted to carry a water connection.

- 24. A stoping machine of the type wherein in the tool actuator is adapted to be supported between an oppositely extending tool and feeding mechanism by engagement of the tool and feeding mechanism with oppositely facing surfaces of the work comprising, in combination, a drill steel, a fluid actuated hammer engine for actuation of said steel, a feed cylinder carried by said engine in lateral offset relation thereto, a feed piston in said cylinder, a feed piston rod for said piston, said rod movable longitudinally of said cylinder but secured against rotation relative to said cylinder, and a work

25. A stoping machine of the type wherein in the tool actuator is adapted to be supported between an oppositely extending tool and feeding mechanism by engagement of the tool and feeding mechanism with oppositely facing surfaces of the work comprising, in combination, a fluid actuated hammer engine for actuating a drill steel, a feed cylinder carried by said engine in lateral offset relation thereto, a feed piston in said cylinder, a feed piston rod for said piston, said rod movable longitudinally of said cylinder but secured against rotation relative to said cylinder, a work engaging end for

40 said rod offset into alignment with said drill steel, said end adapted to permit rotation of the machine relative to the work, a chuck 50 rotatably carried by said engine, said chuck formed for substantially non-rotatably receiving the shank of said drill steel, a fluid actuated motor and reduction gearing carried by said engine for actuating rotation of 55 said chuck relative to said engine, and releasable means effective to prevent rotation of said chuck relative to said engine.

In testimony whereof, I have signed my name to this specification.

GEORGE H. GILMAN.

CERTIFICATE OF CORRECTION.

Patent No. 1,644,120.

Granted October 4, 1927, to

GEORGE H. GILMAN.

It is hereby certified that error appears in the printed specification of the above numbered patent requiring correction as follows: Page 2, line 36, after the word "have" insert the word "shown"; page 6, line 114, claim 22, for the misspelled word "longitudnially" read "longitudinally"; and that the said Letters Patent should be read with these corrections therein that the same may conform to the record of the case in the Patent Office.

Signed and sealed this 1st day of November, A. D. 1927.

M. J. Moore,
Acting Commissioner of Patents.
